UNITED STATES PATENT OFFICE.

WILLIAM G. DUNN, OF CLARINDA, IOWA.

LUGGAGE CARRIER.

Application filed May 22, 1922. Serial No. 562,803.

To all whom it may concern:

Be it known that I, WILLIAM G. DUNN, a citizen of the United States, residing at Clarinda, in the county of Page and State 5 of Iowa, have invented certain new and useful Improvements in Luggage Carriers; and I do declare the following to be a full, clear, and exact description of the invention, such as will enable others skilled in the 10 art to which it appertains to make and use the same.

My invention relates to improvements in luggage carriers and more particularly to those of the form employing toggle links 15 adapted to be clamped upon the running board of an automobile to retain suit cases, camping equipment and other luggage upon the machine. I am aware that numerous devices along this general line have been 20 devised, but it is the aim of my invention to devise a construction and arrangement of parts which will greatly simplify and cheapen devices of the class to which it relates.

25 With the foregoing in view, the invention resides in the novel subject matter hereininafter described and claimed, the description being supplemented by the accompanying drawings.

30 Figure 1 is a side elevation of a luggage carrier constructed in accordance with my invention, showing its application to the running board of an automobile.

Figure 2 is a transverse sectional view on line 2—2 of Figure 1.

Figure 3 is a detail perspective view illustrating the manner of connecting the toggle linkage with the end frames.

40 Figure 4 is an enlarged perspective view showing more particularly the clamp which is employed for connecting the center of the toggle linkage with the running board.

45 Figure 5 is a perspective view of the clamping means associated with the end frames.

Figure 6 is a detail horizontal section on line 6—6 of Figure 1.

50 Figure 7 is a perspective view showing a different form of center clamp which may be used if desired.

55 In the drawings above briefly described, the numeral 1 designates a side guard or longitudinal frame adapted to extend along the outer edge of an automobile running board, said guard or frame preferably consisting of a lazy tong structure formed of

a plurality of toggle links, in order that it may be compactly folded when not in use and may be extended for running boards of different lengths. The ends of the guard 60 1 are connected with a pair of end frames 2 and clamps are associated with these frames for securing them to the running board, these clamps and frames being preferably formed in the manner shown. In this 65 showing, the numeral 3 designates a metal rod which is here bent into triangular shape to form an end frame 2, the base portion 4 of the triangle being extended across the altitude portion 5. The lower end of the 70 vertical portion 5 is received within the channel of an L-shaped channel metal clamping member 6 having a threaded opening through which the base portion 4 is threaded, a nut and washer 7 being threaded on the end of the latter to hold it in place and to also clamp the vertical portion 5 to the clamping member 6. The horizontal arm of the clamping member 6 is adapted 75 to underlie the running board while the 80 base portion 4 is adapted to overlie the same, and a suitable clamping screw 8 is threaded through said horizontal portion of the clamping member for tightly securing the device upon the running board, 85 as will be clear by reference to Figure 2.

By constructing the end frames 2 in or substantially in the manner shown and described, several parts are eliminated which are commonly used, thereby simplifying 90 and cheapening the article, while its efficiency is in no manner decreased.

While any preferred means may be employed for slidably connecting the ends of the side guard 1 with the end frames 2, I 95 prefer on account of extreme simplicity, to bend the endmost links of said guard at an angle in the manner shown, said ends being given a quarter twist and formed with slots 100 9 receiving the vertical portions 5 of said end frames. Also, while it is not essential in all cases that the center of the guard 1 be connected with the running board, I prefer 105 to employ some simple form of clamp for this purpose, one form of this clamp being shown in Figures 1 and 4, indicated by the reference character 10, while the numeral 10^a in Figure 7 illustrates a further form of construction which may be used, both of them being easy to manufacture, and inexpensive, yet very efficient. By employing 110 the construction shown or a similar con-

struction, a simple and cheap device is provided, yet it will be highly efficient and desirable. When extended and clamped to the running board, the side guard 1 will of course prevent luggage from slipping sideways from said running board and the end-frames 2, in addition to rigidly bracing said side-guard, prevent articles held within the latter from moving beyond its ends. 10 Excellent results are obtainable from the several details used and hence they constitute the preferred features of construction, but it is understood that within the scope of the invention as claimed, numerous 15 minor changes may be made.

I claim:

1. A luggage carrier for the running boards of automobiles, comprising a side frame adapted to be disposed in an upright 20 position along the outer edge of the running board, rigid end frames adapted to be disposed in upright position transversely across the running board and being pivotally connected to the ends of said side frame, said 25 end frames including upright rods and horizontal rods having free ends which are disposed adjacent each other, and clamping means carried by said end frames and co-acting with the horizontal rods thereof, said 30 clamping means including brackets to which the free ends of said rods are rigidly connected.

2. A luggage carrier comprising a side-frame, a pair of end-frames connected with 35 the ends of said side-frame, each of said end-frames having a vertical bar and a horizontal bar, the latter being adapted to rest upon the running board of an automobile while said vertical bar is adapted to rise 40 from said running board, the ends of the two bars being in crossed relation, an angular clamping member having a vertical arm and horizontal arm, said vertical arm having a threaded opening through which the 45 aforesaid horizontal bar passes and against which said vertical bar bears in close relation with said horizontal bar, the latter being provided with means securing the former against said clamping member, and means 50 associated with the horizontal arm of said clamping member for engaging the lower

side of the running board and securing said horizontal bar in contact with the latter.

3. A luggage carrier comprising a side-frame, a pair of end frames connected with 55 the ends of said side-frame and extending laterally therefrom, each end frame comprising a single metal rod bent to form the sides of the end-frame, the ends of said rod being positioned horizontally and vertically 60 respectively and disposed in crossing relation, the horizontal end of the rod being adapted to rest on the running board of an automobile while the vertical end thereof is adapted to extend upwardly from the latter, an angular clamping member having a vertical arm through which said horizontal end of the rod passes and against which the vertical end bears, means on said horizontal end of the rod for clamping said vertical 70 end against said clamping member, and means associated with the horizontal arm of said clamping member for engagement with the running board to hold said horizontal end of said rod in contact with the 75 running board.

4. A luggage carrier comprising a side-frame, a pair of end-frames connected with the ends of said side-frame and each including a vertical bar and horizontal bar, said 80 bars having adjacent ends disposed in crossing relation with each other, said horizontal bar being adapted to rest upon a running board while the vertical bar is adapted to extend upwardly therefrom, an L-shaped 85 channel metal clamping member having a threaded opening in its vertical arm through which the end of said horizontal bar extends, the lower end of said vertical bar being positioned against said vertical arm and 90 one of its side flanges between the latter and the adjacent portion of said horizontal bar, means on the latter for clamping said lower end of the vertical bar in place, and means associated with the horizontal arm of said 95 clamping member for engagement with the running board to retain said horizontal bar in contact therewith.

In testimony whereof I have hereunto set my hand.

WILLIAM G. DUNN.
